(57) **CLAIM**

The ornamental design for aircraft interior with plated hardware, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a partial perspective view of the aircraft interior with plated hardware depicting a handle and a light and fan control panel;

FIG. 2 is another perspective view thereof;

FIG. 3 is a partial perspective view thereof showing the light and fan control panel; and,

FIG. 4 is a partial perspective view thereof showing the handle.

The grayed-out areas surrounded by broken lines in the drawings depict portions of the aircraft interior with plated hardware that form no part of the claimed design.

1 Claim, 4 Drawing Sheets
